UNITED STATES PATENT OFFICE.

SAMUEL BUTZ, OF EASTON, PENNSYLVANIA.

SHIRT.

SPECIFICATION forming part of Letters Patent No. 694,133, dated February 25, 1902.

Application filed December 15, 1900. Serial No. 39,978. (No model.)

To all whom it may concern:

Be it known that I, SAMUEL BUTZ, a citizen of the United States, residing at Easton, in the county of Northampton and State of Pennsylvania, have invented a new and useful 5 Shirt, of which the following is a specification.

This invention relates to shirts, and has special reference to the bosoms thereof, the object in view being to provide reliable means whereby the bosom of a shirt may be maintained at all times in proper position.

With an ordinary shirt-bosom there is always a tendency for the bosom to bulge and break, especially when a full-dress vest is being worn, there being nothing to hold the bosom flat. Various expedients have been resorted to to hold the bosom flat against the body and prevent it from bulging and breaking; but such devices have been for the most part undesirable and have in fact failed to accomplish the object for which they were designed.

The present invention contemplates the use, 25 in connection with a shirt having a permanent shirt-bosom and provided with pockets extending along the opposite sides of the bosom, of stiffeners incased within said pockets for preventing the bosom from breaking down or 30 bulging transversely and side tabs arranged at points intermediate the length of the bosom and adapted to be connected with suitable fasteners on the shirt, whereby the stiffeners are drawn in opposite directions or away from 35 each other, thus preventing the bosom from bulging and breaking longitudinally. The stiffeners are preferably curved to conform approximately to the curvature of the body of the wearer, and by the means to be hereinafter more particularly described the bosom 40 as a whole is stretched and held in a flat condition at all times.

In the accompanying drawings, Figure 1 is 45 a front elevation of a shirt constructed in accordance with the present invention and shown applied to the person. Fig. 2 is a front elevation of the shirt removed from the person, the tabs being disconnected and one of the pockets being partially broken away to 50 show the contained stiffener. Fig. 3 is an enlarged detail cross-section through a por-

tion of the shirt and bosom adjacent to one of the tabs.

Similar numerals of reference designate corresponding parts in all the figures of the drawings.

In Fig. 1 I have for convenience in illustrating the nature of the present invention shown a shirt applied to a person with the tabs fastened back at each side of the bosom. 60 1 designates the shirt, and 2 the bosom thereof, the said parts being of the ordinary construction, with the exception that elongated pockets 3 are formed at the opposite sides of the bosom to receive stiffeners 4, the pockets 65 being left open or unstitched at their upper ends in order that the stiffeners 4 may be inserted therein and removed therefrom, it being desirable to remove the stiffeners before sending the shirt to the laundry.

The pockets 3 may bound the side edges of the bosom or may be arranged slightly within the side edges thereof, according to preference and according to the width of the bosom. In full-dress shirts, where bosoms of extra 75 widths are employed, the pockets for the stiffeners should be arranged at points somewhat remote from the side edges of the bosom in order that they may not lose their effect. The pockets 3 may be formed by stitching 80 the several plies or thicknesses of the bosom on parallel lines, the spaces between the parallel rows of stitches forming the pockets, or said pockets may be separately formed and stitched or otherwise applied to the bosom. 85 The stiffeners 4 prevent the bosom from bulging or breaking transversely, and said stiffeners are preferably curved longitudinally, so as to conform approximately to the curvature of the chest.

Tabs 5 are connected to the side edges of the bosom at points intermediate the length thereof, said tabs projecting laterally from the bosom in opposite directions and being provided with buttonholes 6, adapted to connect with buttons 7, secured to the sides of the shirt and preferably adjacent to the lower portions of the armhole-seams. As these tabs are arranged close to the pockets which contain the stiffeners, when the tabs are buttoned back, as shown in Fig. 1, there is a 95 tendency at all times to draw the stiffeners 100

apart, so that while the stiffeners prevent the bosom from breaking down or bulging transversely the tabs hold the bosom stretched transversely and with the aid of the stiffeners prevent the bosom from breaking or bulging longitudinally.

From the foregoing description it will be understood that the bosom is held effectively stretched and flat against the body of the wearer at all times and that this desirable result is attained by the particular combination which exists between the stiffeners and the tabs. The two elements combined in the manner described are therefore essential in order to keep the bosom in perfect condition. It will also be understood that the improvement hereinabove described may be used in connection with shirts of open-front or closed-bosom construction.

Having thus described the invention, what is claimed as new, and desired to be secured by Letters Patent, is—

1. A shirt having a permanent bosom, pockets extending along opposite sides of the bosom, stiffeners contained in said pockets, tabs extending in opposite directions from the bosom at points intermediate the length thereof, and fastening means for said tabs whereby the shirt-bosom is held in shape throughout its entire length, substantially as described.

2. A shirt comprising a permanent bosom, pockets extending longitudinally of the side edges of the bosom, stiffeners removably fitted in said pockets, and laterally-extending tabs connected to the sides of the bosom and adapted to be secured to the shirt, whereby the shirt-bosom is held taut throughout its entire length, substantially as set forth.

3. A shirt comprising a permanent bosom, pockets extending along opposite sides of the bosom, and arranged within the side edges

thereof, removable stiffeners contained within said pockets, and laterally-projecting tabs connected to the sides of the bosom beyond the pockets and centrally disposed with respect to the pockets and having fastening means by which they may be secured to the body of the shirt, whereby the shirt-bosom is held taut throughout its entire length, substantially as described.

4. A shirt comprising a permanent bosom, pockets extending along the sides of the bosom and open at the top and closed at the bottom, curved stiffeners removably inserted in said pockets, and laterally-projecting tabs secured to the sides of the bosom intermediate its length beyond the pockets and having provision whereby they may be removably connected with the body of the shirt, whereby the shirt-bosom is held taut throughout its entire length, substantially as described.

5. A shirt having its bosom and neckband formed as permanent parts thereof, longitudinal pockets extending throughout the bosom along opposite sides thereof, said pockets being open at the top and closed at the bottom, longitudinally-curved stiffeners removably inserted in said pockets, tabs arranged beyond the pockets and extending in opposite directions from the bosom at points intermediate the lengths of the pockets, and fastening means for said tabs, whereby the shirt-bosom is stiffened longitudinally and held transversely, substantially as described.

In testimony that I claim the foregoing as my own I have hereto affixed my signature in the presence of two witnesses.
